UNITED STATES PATENT OFFICE.

CHARLES A. WILLMARTH, OF DETROIT, MICHIGAN, ASSIGNOR TO BENJAMIN W. MARVIN, OF DETROIT, MICHIGAN.

MACHINE FOR WEAVING WIRE FENCES.

No. 847,533.

Specification of Letters Patent.

Patented March 19, 1907.

Application filed September 11, 1905. Serial No. 277,973.

To all whom it may concern:

Be it known that I, CHARLES A. WILLMARTH, a citizen of the United States of America, residing at Detroit, in the county of Wayne and State of Michigan, have invented 5 certain new and useful Improvements in Fence-Looms, of which the following is a specification, reference being had therein to the accompanying drawings.

- 10 > This invention relates to improvements in machines for weaving wire fences, and more especially to machines for weaving fences formed of longitudinally-extending strands and cross-stays which are woven together by twisting the two wires forming each strand in one direction, inserting a stay between said wires, and then twisting the wires in the opposite direction to firmly engage each stay and hold the same in place.
- 15 > The object of the invention is to provide a simple and efficient machine for the purpose, having means for automatically stopping the twisting mechanism when the strands have been given a predetermined number of turns, 20 which means may be quickly and easily adjusted to vary the number of turns and which is so constructed that the operator is precluded from starting the mechanism in the wrong direction—that is, the reversal of 25 the twist after the insertion of each stay is insured.

It is also an object of the invention to provide the device with suitable means for carrying and moving the stay, having adjustable 30 means for automatically limiting its movement to determine and vary the spacing of the stays in the fence, and to provide certain other new and useful features in the construction, arrangement, and combination of 35 parts, all as more fully hereinafter described, reference being had to the accompanying drawings, in which—

Figure 1 is a side elevation of a device embodying the invention; Fig. 2, a plan view of 40 the same; Fig. 3, an enlarged transverse section through one side of the frame just at the rear of the carriage, and Fig. 4 is an enlarged longitudinal section through one of the twist- 45 ers and adjacent parts.

50 As shown in the drawings, 1 is a suitable supporting-frame, upon which near its forward end are mounted in suitable bearings two transversely-extending shafts 2, each provided with a series of sheaves 3, spaced apart

according to the desired spacing of the longitudinal wires or strands 4 of the fence and over which said strands pass and are guided, each strand consisting of two wires, which are taken from suitable reels (not shown) and first passed through a tension device 5, 60 provided for each strand, consisting of a suitable bracket adjustably secured by a set-screw to a transverse bar 6 on the frame, and upon which bracket is journaled a series of small rolls over and beneath which the wires 65 are passed to create the desired amount of friction and resist the too free passage of said wires. From the tension devices the wires pass beneath the sheaves on the first shaft and then over those on the second shaft, said 70 shafts being provided at one end with like intermeshing gears 7 to cause the same to turn together at the same speed.

Mounted in suitable bearings on the frame intermediate its ends is a transverse shaft 8, 75 upon which is adjustably secured a series of worm-gears 9, in mesh with a series of similar gears 10, each formed with two holes 11, extending longitudinally therethrough and through its extended hub portion 12, through 80 which holes the wires of each strand are passed and forming twisters for the strands. Adjustable bearing-blocks 13 are provided to receive and within which the hub portions of the twistlers freely turn, and standards 14 are 85 secured to the frame adjacent to the shaft 8, to which standards two parallel horizontally-extending angle-bars 15 are bolted and between which bars the bearing-blocks are supported. Flanges 16 on the blocks extend 90 upwardly and downwardly therefrom at each end in engagement with the bars and set-screws 17, extending through one of the flanges, engage the bars at one side and hold the blocks in any position to which they may 95 be adjusted longitudinally of the bars. A disk 18 is secured by bolts or top screws to the end of the hub of each twister to secure the same within its bearing-block and formed integral with this disk is a tailpiece or 100 spreader 19, having a groove 20 in each edge for the wires, said grooves ending in holes in the disk opposite the holes for the wire in the twister.

The shaft 8 is driven by two belt-pulleys 21 105 and 22, loosely mounted on the projecting end of said shaft and connected to the shaft to turn the same by means of a clutch 23,

splined on the shaft between said pulleys and adapted to be moved longitudinally thereof to engage its teeth with teeth formed on the adjacent ends of the hubs of the pulleys. 5 The space between the said ends of the hubs is such that when the clutch is moved to its mid-position it will be out of engagement with both, so that motion will not be transmitted thereby from either pulley to the 10 shaft, and the twisters will stand still.

Extending parallel with the projecting end of the shaft 8, upon which the pulleys are mounted, is a cam-shaft 24, which receives a 15 slow motion from the shaft 8 by means of a large gear 25 on its outer end in mesh with a small gear 26 on the twister-shaft 8, and adjustably secured on said cam-shaft are two opposed disks 27, each provided with a cam or lug 28 on its face to engage the end of a 20 shifting lever 29, which projects between said disks. The opposite end of said lever is pivoted to the frame and intermediate its ends to the clutch 23, so that when said clutch is in engagement with one pulley its free end 25 will be in the path of one of the cam-lugs, and when the twister-shaft has been turned a certain number of revolutions to put the required number of twists in the wire said cam or lug will engage said lever and move 30 the same to mid-position, thus moving the clutch out of contact with the pulley and stopping the twisting operation.

30 is a spacer-carriage or movable support for the cross-stays or pickets of the fence, said carriage consisting of a top plate 31, formed with a series of upwardly-extending fingers 32 along its forward edge, between which the wires pass from the twisters, and vertical ends extending downward adjacent to each 40 side bar of the frame, to the inner face of which bar a track or way 33 is secured to receive a rib 34 on said ends adapted to slide therein. The fingers are evenly spaced throughout the length of the carriage, preferably one inch between centers, and thus form 45 a scale to indicate the spacing of the strands.

Bearings are provided on the frame for a transverse driving-shaft 35, which is provided with a driving-pulley 36 at one end 50 and intermediate its ends with a pinion 37, loosely mounted thereon in mesh with a gear 38 on a counter-shaft 39. Motion is transmitted from said driving-shaft to the pinion through a clutch 40, splined on the shaft to 55 slide longitudinally thereof into engagement with teeth formed on the hub of said pinion, and from said counter-shaft motion is transmitted to a rock-shaft 41 by means of a pinion 42 on the counter-shaft and a large gear 60 43 on the rock-shaft. Secured to the rock-shaft inside the frame, near each side thereof, is a rocker-arm 44, each of which arms is connected to one end of the carriage by a rod 45, so that when the clutch 40 is in operative position 65 the rock-shaft will be turned and the

carriage drawn rearwardly on its ways, each arm being provided with a series of openings for the engagement of said rods in order that the distance which the carriage will be moved by said arms may be varied.

70

The travel of the carriage is automatically limited by providing a shifting lever 46, which is pivoted to the frame at its rear end, and extending forwardly beneath the clutch is pivotally attached thereto intermediate 75 its ends. The forward end of said lever extends beneath the carriage and beyond the twisters, and to this end is attached a coiled spring 47 to normally hold the lever shifted to a position to hold the clutch in operative position. To the top of the side bar of the frame opposite the forward end of said lever is secured a plate 48, having a slot 49 extending from near its inner edge and forward end diagonally across the same to near its outer 80 edge and rear end where the slot is formed with an offset 50. An operating-bar 51 is pivotally attached at one end to the lever near its forward end, and at its opposite end said bar is provided with a pin 52 to engage 85 the slot 49. An operating-rod 53 is pivotally secured at one end to the carriage, and an adjustable hook 54 is secured to said rod to engage the operating-bar as the carriage nears the rear end of its stroke and swing said bar 90 rearwardly, forcing the pin 52 rearwardly in its slot, and thus, by reason of the diagonal direction in which said slot extends, shifting the lever 46 to disengage the clutch 40 and stop the transmission of motion from the 95 driving-shaft. When said pin reaches the rear end of its slot, it drops into the offset 50, and thus the shifting-lever is locked in this position. On a projecting end of the rock-shaft 41 is secured a handle 55, by means of 100 which the operator may turn said shaft backward when the clutch has been thrown out by the rearward movement of the carriage, as described, to return the carriage to the forward end of its movement.

110

Mounted in suitable bearings on the frame to slide transversely thereof is a shifting-rod 56, provided with a handle at one end and pivotally attached to the shifting lever 29 at its opposite end, and pivoted intermediate 115 its ends upon a cross-bar of the frame opposite the operating-bar 51 is a rocker-bar 57, having a slot in its rear end to receive a pin 58 on the rod 56 and formed with a forked forward end 59 to receive and engage a pin 120 60 on the bar 51, when said bar is moved into locked position.

At the extreme rear end of the frame is mounted a transverse shaft 61, having secured thereon a drum 62, upon which the fence is wound after passing over a supporting-roller 63 on the frame at the rear of the counter-shaft 39. To turn this drum and wind the fence thereon as the carriage moves rearwardly, a pinion 64 is secured on the end 130

of the drum-shaft in mesh with a gear 65, loosely mounted on a stub-shaft 66, and a lever 67, also loosely mounted on the stub-shaft, is provided with a weighted pawl 68 to engage the gear and turn the same when said lever is moved forward by a connecting-rod 69, attached to its lower end at one end and to a downwardly-extending arm 70 on the rock-shaft 41 at its opposite end.

10 The roll of fence constantly increases in diameter as the fence is wound thereon, and as the drum will be turned the same distance each time by the lever 67 it is necessary to make provision for such variation. For this purpose the said lever is slotted longitudinally to receive a stud-bolt 71 on a block 72, through an opening in which block the rod 69 passes, and said bolt is adjustably secured in said slot by a hand-wheel 73 on its screw-threaded outer end engaging the outer side of the lever and clamping the block thereto. The point of attachment of the rod to the lever may thus be quickly and easily changed to vary the throw of the lever. To obviate the necessity for changing this adjustment often, the rod 69 is extended some distance through the block in which it is free to slide longitudinally, and between said block and a nut 74 on the end of the rod a coiled spring 75 is sleeved, 30 a nut 76 being provided on the rod to engage the opposite side of the block. When the resistance to the turning of the drum becomes greater than the resistance of the spring 75, said spring will yield and permit the rod to slide in the block, thus shortening the throw of the lever, so that the drum will not be turned as far. When the carriage is run back to its forward position by the handle 55, the lever 67 will be swung back to the 40 position shown in Fig. 1, its pawl slipping over the teeth of the gear, and the fence is prevented from unwinding by a spring-pawl 77 on the frame engaging said gear.

The parts being in the position shown, with 45 a stay 78 in place between the diverging wires of the strands, the shaft 8 will be driven by the pulley 22 and the twisters rotated to twist the wires together, the stay and fence being carried rearwardly by the 50 carriage at the same time. When the required number of twists have been put in the wires, the cam 28 will engage the end of the lever 29 and shift the clutch to mid-position, and at the same time the movement of the 55 carriage will be stopped by the shifting of the lever 46. The operator by means of the handle 55 may then run the carriage back to the forward end of its movement with the fingers 32 adjacent to the twisters, and as the 60 cam-disks 27 may be secured to the shaft in a position to throw the clutch and stop the twisters in any desired position by reason of the shafts 8 and 24 being geared together said twisters are stopped with their holes 11 in

vertical alinement, and the next stay may be 65 easily inserted between the diverging wires at the rear side of the fingers. To again start the twisters and carriage, the operator will shift the rod 56, which by reason of its pivotal attachment to the lever 29 will move the 70 clutch 23 into engagement with the pulley 21 and cause the twisters to be driven in the opposite direction to that in which they were just previously turned, and by reason of the engagement of the pin 58 on said rod with 75 the end of the rocker-bar 57 said bar will be turned, and the pin 60 on the operating-bar 51 being within the forked end of said rocker-bar said operating-bar will be moved and its pin disengaged from the offset 50 in the slot 80 49, thus unlocking said operating-bar and permitting the spring 47 to throw the clutch 49 into engagement with its pinion. When the twisting operation is stopped by the engagement of the cam 28 with the end of the 85 lever 29, said cam projection remains in contact with said lever until the lever is shifted by the operator, and therefore said lever can only be shifted toward the opposite cam-disk, thus insuring the reversal of motion of 90 the twisters.

The number of turns which shall be made may be quickly and easily changed by shifting the cam-disks on their shaft to change the relative positions of the cam projections 95 thereon, and the spacing between the strands may be changed as desired by shifting the worm-gears 9 on their shaft and slackening the set-screws 17, so that the twisters may be correspondingly moved between their supporting-bars 15. 100

Having thus fully described my invention, what I claim is—

1. In a fence-loom, the combination of a series of twisters having extended hub portions provided with longitudinal holes for the passage of the wires to be twisted, standards on the machine-frame, angle-bars secured to the standards with their adjacent faces in parallelism, a series of bearing-blocks adjustably supported between said angle-bars to receive the hubs of the twisters which turn freely therein, flanges on said blocks engaging the edges of the angle-bars, set-screws extending through said flanges and engaging the bars to adjustably secure the blocks in place, and a tail-piece secured to the end of each hub opposite the twister to engage the block and hold the hub therein and formed with grooves along its edges for the wires. 115 120

2. In a fence-loom, the combination with the supporting-frame, of a transverse shaft mounted in bearings on said frame, a series of twisters supported on the frame adjacent to said shaft, worm-gears to transmit motion from said shaft to the twisters, a pulley loosely mounted on said shaft, a clutch to connect the pulley with the shaft, a cam-

shaft, gears for transmitting motion from the transverse shaft to the cam-shaft, and a cam on said shaft to operate the clutch.

3. In a fence-loom, the combination with 5 the supporting-frame, of a transverse shaft mounted on said frame, a series of twisters having teeth on their periphery, worm-gears on said shaft to engage the teeth on the twisters, two pulleys loosely mounted on said 10 transverse shaft, a clutch movable longitudinally on the shaft into or out of engagement with either pulley, a shifting lever for the clutch, a cam-shaft extending parallel with the transverse shaft, gears on said shafts to 15 transmit motion from one to the other, opposed cam-disks adjustably secured to the cam-shaft between which the end of the operating-lever projects, said cams being adapted to engage and move the lever to disconnect the clutch from the pulleys and stop the 20 twisters, and a hand-lever for moving said clutch to throw the same into operative position.

4. In a fence-loom, the combination with 25 the supporting-frame and a series of twisters mounted thereon, of a carriage movable on the frame toward and from the twisters, a transverse driving-shaft on the frame, a rock-shaft, arms on the rock-shaft, rods connecting the ends of the arms with the carriage, a pinion loosely mounted on the driving-shaft, 30 a clutch to connect said pinion to said shaft, gears for transmitting motion from the pinion to the rock-shaft, and means operated by 35 the movement of the carriage for throwing the clutch out of engagement with the pinion to stop the movement of the carriage.

5. In a fence-loom, the combination with a series of twisters, of a shaft for transmitting 40 motion to said twisters, a clutch for transmitting motion to the shaft, means for automatically moving the clutch to stop the transmission of motion to the twisters, a carriage adapted to move toward and from the 45 twisters, means for moving said carriage away from the twisters, a clutch to transmit motion to said means, means moved by the movement of the carriage for throwing the last-named clutch to stop the carriage, and a 50 shifting rod simultaneously operating each means for moving each clutch, to throw both clutches into operative position.

6. In a fence-loom, the combination with a series of twisters, of a shaft to transmit motion 55 to said twisters, two pulleys loosely mounted on said shaft at a distance apart and formed with clutch-teeth on the adjacent ends of their hubs, a clutch splined on the shaft between said pulleys and adapted 60 to be moved into engagement with either or out of engagement with both, a lever to shift said clutch, a cam-shaft extending parallel with the other shaft, a large gear on the cam-shaft in engagement with a pinion on the 65 other shaft, opposed cam-disks on the cam-

shaft, a cam projection in each disk to engage the projecting end of the lever and throw the clutch out of engagement with both pulleys, and an operating-rod to shift the lever, whereby the lever is prevented by 70 the engagement of one of said projections, from being moved by the rod toward the disk carrying that lug and thus the clutch is prevented from being reengaged with the pulley from which it has just been disengaged by 75 said projection.

7. In a fence-loom, the combination with a supporting-frame, of a series of twisters and means for turning the same, a track on the frame, a carriage movable toward and from 80 the twisters on said track, a transverse driving-shaft on the frame, a transverse rock-shaft, arms on the rock-shaft, rods connecting the ends of said arms with the carriage, a pinion loose on said driving-shaft, a train of 85 gearing to transmit motion from the pinion to the rock-shaft, a clutch on the driving-shaft to secure the pinion to said shaft, a lever to move said clutch, a spring to normally hold the clutch in operative position, an operating-bar attached to the free end of the lever for moving the clutch, a rod attached to the carriage, and a hook on the rod to engage the operating-bar.

8. In a fence-loom, the combination with 95 the supporting-frame, of a series of twisters, a transverse shaft, worm-gears on the shaft to turn the twisters, a clutch to transmit motion to the shaft, means for automatically moving said clutch out of operative position, 100 a shifting-rod to move the clutch into operative position, a reciprocable carriage, means for moving said carriage, a clutch to control said means, a lever to move the clutch and stop the carriage, an operating-bar pivotally 105 attached to the free end of said lever to move the lever, a spring to move the lever in the opposite direction, locking means for said bar, means on the carriage for moving the bar into locked position, and a lever connected to 110 the shifting-rod turned thereby to unlock the operating-bar.

9. In a fence-loom, the combination with a series of twisters and means for turning the same, of a reciprocable carriage, a driving-shaft, a rock-shaft, a train of gears connecting said drive and rock shafts, a clutch to disconnect the gearing from the drive-shaft, upwardly-extending rocker-arms on the rock-shaft, rods connecting said arms with the carriage, a downwardly-extending rocker-arm on the end of said rock-shaft, a drum upon which the fence is adapted to be wound, a pinion on the shaft of said drum, a stub-shaft, a gear loose on said stub-shaft in engagement with the pinion, a swinging arm loose on the stub-shaft, a pawl carried by said arm to engage and turn the gear in one direction, a spring-pawl to prevent the gear from turning in the opposite direction, a 125 130

block adjustably secured to the lower end of said arm, a rod passing through an opening in said block at one end and pivotally attached to the downwardly-extending rocker-arm at its opposite end, a nut on the projecting end of the rod and a nut to engage one side of the block, and a spring sleeved on the rod between the opposite side of the block and the nut on the end of the rod.

10 10. In a fence-loom, the combination with a supporting-frame, of a transverse shaft mounted in bearings intermediate the ends of the frame, standards on the frame adjacent to said shaft, parallel supporting-bars secured to said standards, bearing-blocks adjustably secured between said bars, twisters formed with peripheral teeth and having extended hubs to engage the bearings, worm-gears on the transverse shaft to engage said teeth, tail-pieces secured to the ends of the hubs and having grooves for the wires passing through the twisters, parallel shafts mounted in the forward end of the frame, gears connecting said shafts, sheaves on said shafts, tension devices on the forward end of the frame provided with two or more parallel friction-rolls, two pulleys loosely mounted on the transverse twister-shaft, a clutch splined on the shaft between said pulleys, a shifting-lever pivotally attached at one end to the frame and intermediate its ends to the clutch, a cam-shaft, cams on said shaft to engage the free end of the shifting-lever, a handled operating-rod attached to said shifting-

lever and extending across the frame, tracks 35 on the frame, a carriage on said tracks, a driving-shaft, a clutch on said driving-shaft, a pinion adapted to be engaged by the clutch, a rock-shaft, gears connecting the rock-shaft and pinion, upwardly-extending arms on the 40 rock-shaft, rods connecting the arms with the carriage, a downwardly-extending arm on one end of the rock-shaft, a handle-lever on the rock-shaft, a drum mounted in bearings on the rear end of the frame, gears for 45 turning the drum, a swinging arm, a pawl carried by said arm to engage and turn the gears, a rod adjustably attached at one end to said swinging arm and at its opposite end to the downwardly-extending rocker-arm a 50 long lever pivotally attached to the clutch on the driving-shaft, a spring to move said lever in one direction, an operating-bar attached at one end to said lever, a plate on the frame having a diagonal groove formed with 55 an offset at one end, a pin on the operating-bar to engage the groove, a rod on the carriage, a hook on the rod to engage the operating-bar, and a lever pivoted intermediate 60 its ends on the frame and attached at one end to the handled operating-rod and adapted to engage the operating-bar at its opposite end.

In testimony whereof I affix my signature in presence of two witnesses.

CHARLES A. WILLMARTH.
